UNITED STATES PATENT OFFICE.

CHARLES E. CAMPBELL, OF LYNN, MASSACHUSETTS.

X-RAY APPARATUS.

1,274,852.

Specification of Letters Patent. Patented Aug. 6, 1918.

Application filed May 5, 1913. Serial No. 785,538.

To all whom it may concern:

Be it known that I, CHARLES E. CAMPBELL, a citizen of the United States, residing at Lynn, in the county of Essex and State 5 of Massachusetts, have invented certain new and useful Improvements in X-Ray Apparatus; and I do hereby declare the following to be a full, clear, and exact description of the invention, such as will enable others skilled in the art to which it appertains to 10 make and use the same.

The present invention relates to X-ray apparatus, and more particularly to apparatus for stepping up and rectifying an alternating current to supply a high tension unidirectional current for exciting an X-ray tube.

The object of the present invention is to 20 reorganize and improve apparatus of this type. The improvements particularly relate to the winding of the step-up transformer and the current regulating means for the transformer; to the rectifier for rectifying the high tension alternating secondary current of the transformer into a high tension unidirectional current for exciting an X-ray tube; to a voltmeter and its connections for determining the voltage of the high tension current delivered to an X-ray 30 tube; to a switch in the primary circuit of the transformer for changing the direction of flow of the uni-directional current, and a polarity indicator for indicating the proper position of the switch; to the adaptation of the polarity indicator for use as a synchronizer for the rectifier driving motor; to mechanism for cutting off the current from the X-ray tube after a predetermined exposure; to the construction of the terminals to which 40 an X-ray tube is connected, and to certain other features of construction hereinafter described and claimed, the advantages of which will be apparent to those skilled in the art.

In the drawings, which illustrate the preferred embodiment of the invention, Figure 1 is a diagrammatic view showing the wiring connections; Fig. 2 is a side elevation of the apparatus, one of the panels being removed to show the motor and rectifier; Fig. 3 is a view taken from the inside of the casing, showing the pulley connections for turning the spark-gap arms; Fig. 4 is a detail view of the high tension rectifier; Fig. 5 is a sectional view of one of the high tension current terminals for the X-ray tube;

Fig. 6 is a section of the regulator terminal; Fig. 7 is a cross-section along the line 7—7 of Fig. 5; and Fig. 8 is a detail view showing the time-controlling switch.

In the illustrated embodiment of the invention, the apparatus is inclosed in a wooden casing 1. On the front of the casing is the switchboard 2 and below it, a rheostat 3 for the transformer primary. On the left hand side of the casing is a hard rubber panel 4 through which project high tension anode and cathode terminals, A and C respectively, and the regulator terminal R. In the base of the casing is located the 60 alternating current step-up transformer 5. In the upper part of the casing is located the motor 6 which drives the rectifier 7 for rectifying the secondary current of the transformer so as to furnish a high tension 70 uni-directional current for exciting the X-ray tube. The X-ray tube 10 is mounted upon any suitable support and is connected, through flexible leads, to the anode and cathode terminals.

The current is derived from a single-phase three-wire alternating current system. The voltage between the two outside wires 11 and 12 is 220 volts, and the voltage between the middle or neutral wire 13 and 80 each of the outside wires is 110 volts. A switch (not shown) external to the apparatus is inserted between the supply wires 11, 12 and 13 and the supply mains. The transformer 5 is designed to operate under 90 a primary voltage of 220 volts, and it derives its primary current from the two outside wires 11 and 12 of the supply circuit. The transformer current is led through a two-pole double throw reversing switch 14, 95 a time switch 15, the rheostat 3 and a voltage regulator 16, to the transformer primary. The high tension secondary current of the transformer is rectified by the rotary rectifier 7 into a high tension uni-directional current, which is delivered through the external anode and cathode terminals A and C to the X-ray tube. The uni-directional current delivered to the X-ray tube is a fluctuating direct current consisting of the higher-voltage part of each wave of the alternating current. In order to enable the operator to readily determine the voltage of the uni-directional current supplied to the X-ray tube, a voltmeter 20 is connected with the secondary of the transformer 5. The time switch 15 is controlled

2
by a time-controlling device 21 which may be set to cause the primary circuit of the transformer to be opened after a predetermined time.

- 5 The motor 6, which drives the rotary rectifier 7, is designed to operate upon 110 volts and is connected between one of the outside wires and the neutral wire of the three-wire supply system, through a starting switch 22. The motor, the construction of which is not a part of the present invention, has its armature wound like a single phase converter. The motor has a four-pole laminated field which is so wound that the motor can be started and brought up to speed as a commutated single phase alternating current motor, and then after the motor is brought up to speed, it can be run as a single phase synchronous motor. When the starting switch 22 is thrown up into contact with the switch contacts 23 and 24 the current is led to the motor commutator 25 and the starting fields, and the motor is started as a commutated alternating current motor. 20 When the starting switch 22 is thrown down into contact with the stationary switch contacts 26, 27, 28 and 29, the current is led to the slip rings 30 and the running field-winding, and the motor is run as a synchronous 25 motor in step with the exciting current of the transformer 5.

When the motor comes up to synchronous speed and the switches in the primary circuit of the transformer are closed, it is a matter of chance whether the anode and cathode terminals A and C are positive and negative in sign respectively, or vice versa. This is due to the fact that the angular position of the rotor of a four-pole synchronous 35 motor of this type may, with relation to the phase of the current wave, differ 90° of the angular position of the rotor or 180° of the current wave each time the motor is used, and consequently the angular position of the disk may, with relation to the instantaneous polarity of the stationary rectifier contacts, differ 90° of the angular position of the disk or 180° of the current wave to be rectified. 40

- 50 In order that the X-ray tube may be always connected the same way to the terminals, or may be left connected, it is desirable that when the tube is used, the anode terminal on the machine shall always be positive and the cathode terminal always negative in sign. The direction of current flow in the transformer 5 may be reversed by means of the reversing switch 14 so that if a current of negative polarity is delivered to the 55 anode terminal by the rectifier 7, the phase of the high tension alternating current delivered to the rectifier 7 may be changed 180° by throwing the reversing switch and thus the anode terminal may be changed to 60 the proper positive polarity.

In order to indicate which way to throw the reversing switch 14 to get the proper positive and negative polarity at the anode and cathode terminals respectively, a polarity indicator 40 is mounted upon the switch-board and is connected, through a rectifier 41 mounted upon the end of the motor shaft, to the supply wires 12 and 13. The polarity indicator 40 is a direct current volt-meter in which the indicating needle has its zero position in the middle of the scale, the ends of which are marked "Up" and "Down" respectively. The polarity indicator 40, like most direct current volt-meters, has a permanent magnet, and when the current flows in one direction through the volt meter the needle will swing to the position marked "Down", and when the current flows in the opposite direction the needle will swing to the position marked "Up". The rectifier 41 is a disk of insulating material having four metallic contacts 42, 43, 44 and 45 spaced 90° apart around its periphery, the contacts 42 and 45 and the contacts 43 and 44 being connected together in pairs as indicated in Fig. 1. Disposed around the periphery of the rectifier disk and bearing against its periphery are four brushes 46, 47, 48 and 49. The oppositely disposed brushes 47 and 49 are connected, through lead wires 50 and 51, to the polarity indicator 40, and the oppositely disposed brushes 46 and 48 are connected, through lead wires 52 and 53 respectively, to the supply wires 12 and 13. The rectifier 41 acts to rectify the alternating current led over the wires 52 and 53 and delivers a uni-directional current to the polarity indicator over the wires 50 and 51. The direction of this uni-directional current depends upon the relative position of the rotary rectifier disk with respect to the instantaneous polarity of the brushes 46 and 48, or, in other words, the direction of the uni-directional current depends upon the angular position of the motor rotor with respect to the phase of the alternating current wave. 100

The connections with the polarity indicator 40 are such that when the indicating needle of the polarity indicator points to "Down", the angular position of the motor rotor with relation to the phase of the current wave is such that the reversing switch 14 should be thrown to its "down" position, in which it is illustrated in Fig. 1, to cause the anode terminal A to have a positive polarity. After the reversing switch has been thrown to its "down" position, the needle of the polarity indicator 40 continues to point to "Down" and so continues to indicate to the operator that the anode and cathode terminals are maintained at positive and negative polarity respectively. Of course, if the polarity indicator points to "Up", the reversing switch 14 is to be thrown up. 110 120 125 130

The polarity indicator 40 also serves as a synchronizer to indicate when the motor 6 is brought into step with the current, and consequently, when to throw the starting switch 22 from starting to running position. As the motor comes up to synchronism, the needle of the polarity indicator vibrates, the rapidity of vibration decreasing as the motor speed approaches that of synchronism.

5 10 The rotary rectifier 41 operates, when the motor is running at synchronous speed, to cut off the crests of the current waves and deliver them to the polarity indicator 40. Consequently, when the needle of the polarity indicator remains stationary at its maximum displacement, the operator, who is watching the needle, knows that the motor is running at synchronous speed, and he may then throw the starting switch 22 from 20 starting to running position.

A detailed description of some of the parts which have already been generally described will now be given.

The transformer 5 is a high tension transformer of the core type. The laminated iron core 60 has two legs 61 and 62 connected by end yokes 63 and 64. Upon the leg 62 is wound the secondary 65 of forty-four thousand turns, which is divided into four 25 divisions of coils of eleven thousand turns each. Forty-four turns of the secondary, located at about the middle of the leg 62, are of heavier wire than the remainder of the secondary, as indicated by the heavier 30 line 66 in Fig. 1. The section of heavier wire is used because it carries both the current for the X-ray tube and the current for the volt meter. Taps are brought out from each end of this section of forty-four turns 35 of heavier wire and are connected, through lead wires 67, with the volt-meter 20. The volt-meter, therefore, gets one thousandth of the total secondary voltage. The heavier turns 66 are located at the middle of the 40 secondary, where the magnetic leakage is the least, and where the best general average of the voltage induced in the secondary can be taken. The volt-meter 20 reads directly in volts, and by multiplying the reading by one thousand the entire secondary 45 voltage is got. One of the volt-meter lead wires 67 is grounded, through a safety connection 68, to the primary winding of the transformer and thus to the supply circuit, 50 so that the danger of high voltage discharges from the volt-meter is guarded against. The safety connection 68 is approximately at the middle of the entire secondary winding, so that the voltage 55 between either the anode or cathode terminals A and C and ground is only half that of the entire secondary transformer. A second safety connection 87 is provided to ground the transformer core 60 upon the primary 60 winding of the transformer and so prevents 65

the accumulation of any high tension charges on the transformer core.

The value of the safety connection between the leadwires 67 and the primary winding of the transformer resides in the fact that 70 this connection, which is a permanent part of the self-contained apparatus, always necessarily results in grounding the voltmeter upon the source of current by which the transformer is energized, so that it is 75 impossible to connect up the apparatus for use without automatically protecting the voltmeter by this ground. Any potential which may be conducted to the voltmeter from the source of alternating current by 80 which the transformer is energized, is so much lower than the high potentials or static charges against which it is desired to guard the voltmeter, that this ground or connection is practically as good as a direct connection to earth. 85

The high tension secondary of the transformer is connected, through lead wires 69 and 70, with the oppositely disposed stationary contacts 71 and 72 of the rotary 90 rectifier 7. The primary winding 80 of the transformer is divided into two sections 81 and 82 which are always in circuit, and four regulating sections 83, 84, 85 and 86 which, by means of the voltage regulator 16, may 95 be thrown into series with the sections 81 and 82. The section 81 consists of thirty-seven turns of wire wound on the same leg 62 as the secondary winding and inside of the secondary winding. The section 82 consists of forty-three turns of wire wound on the other leg 61. There are, therefore, eighty turns always in circuit, and these eighty turns are about equally divided between the leg 62 upon which the secondary 100 is wound and the opposite leg 61. The arrangement of primary turns is such that although when the transformer secondary is short-circuited by a short circuit connection between the anode and cathode terminals, 105 the transformer is not dangerously overloaded or burned out, nevertheless, the magnetic linkage between the primary and secondary is such as to make an efficient transformer. The primary section 81 which is 110 wound beneath the secondary has very good magnetic linkage with the secondary, while the primary section 82 on the other leg has, by reason of the magnetic leakage, a poor magnetic linkage with the secondary as 115 compared with the section 81. The section 82 thus acts somewhat after the manner of a choke coil to prevent an excessive current when the secondary is short circuited. If the entire eighty turns were on the same 120 leg as the secondary, the transformer would admit too great a primary current when the secondary was short-circuited. If the whole eighty turns were on the other leg 61 of the transformer, the poorer magnetic linkage 125 as 130

would not permit the transformer to supply as large a secondary current as with the arrangement illustrated. With the division of the primary turns as herein described, the 5 greatest secondary current compatible with safety against damage upon short circuiting is attained. The regulating turns 83, 84, 85 and 86 are used only when it is desired to decrease the secondary voltage and they are, 10 therefore, placed on the leg 61 where they have a comparatively poor magnetic linkage with the secondary. They, therefore, not only do not occupy the more valuable space next the secondary, but also they are thrown 15 into circuit to reduce the voltage, and act somewhat after the manner of choke coils to regulate the current.

One end of the primary winding is connected, through the lead wire 90, to the 20 rotatable contact arm 91 of the adjustable rheostat or resistance 3. The resistance is connected, through a lead wire 92, to the time switch 15 and has a number of taps 93 brought out to contacts 94 over which 25 the arm 91 is moved to throw more or less resistance in series with the transformer to regulate the current. The sum total of the resistance 3 is about eighteen ohms.

From the ends of the primary trans- 30 former coils 83, 84, 85 and 86 lead wires 95, 96, 97, 98 and 99 are brought out to contacts 100, 101, 102, 103 and 104 of the voltage regulator 16. The movable arm 105 of the voltage regulator is connected, through a 35 lead wire 106, to the time switch 15. The movable arm 105 is moved over the contacts to throw more or less of the regulating sections into series with the primary and thus vary the secondary voltage of the trans- 40 former. When the contact arm 105 is on the contact 100 and all of the regulating turns are cut out of circuit, the secondary voltage is one hundred and twenty thousand volts. As the contact arm is moved onto the contact 45 101, the secondary voltage is reduced to one hundred and ten thousand volts. When on the contact 102, the secondary voltage is one hundred thousand volts. When on contact 103, the secondary voltage is seventy-five 50 thousand volts. When on contact 104, the secondary voltage is fifty thousand volts. Beyond contact 104 is an auxiliary contact 55 107 which is connected, through a five-ohm resistance 108, to the contact 104. It will be evident that the resistance 108 can be put in 60 series with the transformer primary only when all of the regulating turns are in series and the transformer is consequently taking in less current than when the regulating coils are not in series. Consequently, 65 by virtue of its position, the resistance 108 is never called upon to carry as great a current load as the resistance 3, and can, therefore, be made of much finer wire, thus cheapening its construction. The resistance 108

is intended to be used as an additional means to cut down the current when the apparatus is used for fluoroscopic work or for electro-therapeutic X-ray treatments.

The primary circuit of the transformer is arranged to be broken by the time switch 15, which is controlled by a timing device 21 which can be set to open the switch 15 after a predetermined number of seconds exposure to the X-rays. The time switch 15 is a two-pole single-throw switch, the two blades 120 and 121 of which are connected, through the rheostat 3 and voltage regulator 16, to the transformer. The two stationary switch contacts 122 and 123 of the time switch are connected with the switch blades of the reversing switch 14. The time switch has two springs 124 which tend to open the switch. The time switch is held closed, against the tension of the springs 124, by means of a pivoted latch 125 which projects through the switchboard panel. The latch 125 is arranged to be released by the timing device 21. The connection between the latch and the timing device 21, and the construction of the timing device are not shown, as such constructions are old and well-known in the art and constitute no part of the present invention. On the face of the timing device 21 is a scale divided into seconds and a pointer or arm 127 which is movable over the scale. The pointer 127 can be moved over the scale and set at any number of seconds, and thereafter when the timing device is set into operation it operates, after the number of seconds at which the pointer is set, to lift the latch 125 and allow the time switch 15 to open. The timing device 21 is set into operation by an electro-magnet 130 which is connected, through the lead wire 131, to the switch blade 120 and, through the lead wire 132 and the single-pole single-throw switch 133, to the switch blade 121. The timing device, although set, does not begin to operate until current passes through the electro-magnet 130. When the tube is to be run continuously and the timing device is not desired, the switch 133 is opened so that the timing device is not set into operation. When a short and definitely timed exposure is desired, the switch 133 can be closed, the pointer 127 set at the desired number of seconds, and the time switch 15 closed. As soon as the time switch 15 is closed, the electro-magnet 130 sets the timing mechanism into operation and the switch 15 is opened after the desired time.

The high tension rectifier 7 comprises a rotary disk 140 mounted on the end of the 125 motor shaft to turn in the direction indicated by the arrow, and the stationary contacts 71, 72, 141 and 142. Oppositely disposed at the periphery of the disk are two conducting plates or bridging conductors 130

143 and 144, secured to the side of the disk 140 by means of bolts 145. These bridging conductors each span about 90° of the periphery of the disk. While the bridging conductors might be arranged to span the 90° of the periphery of the disk by an arrangement of contact plates spaced 90° apart and connected together by wires similar to the construction of the rectifier disk 41, it is, nevertheless, preferred to use the two arcuate conducting plates illustrated, which extend along the periphery of the disk and are consequently at a maximum distance from the shaft throughout their length. The edge 15 of the disk behind each of the plates 144 is cut away at 146 to prevent the arc formed upon breaking the contact from running along the surface of the disk. The contacts 71, 72, 141 and 142 are disposed 90° apart 20 about the periphery of the disk 140 and close to, but not touching, the periphery of the disk. With the high tension voltage employed, the current has no difficulty in jumping from the stationary to the movable contacts. The oppositely disposed contacts 71 and 72 are connected to the secondary of the transformer, and the oppositely disposed stationary contacts 141 and 142 are connected, through the lead wires 150 and 30 151, to the anode and cathode terminals A and C respectively of the X-ray tube which constitutes the load. When the motor is in synchronism and the switch 14 is thrown into the position indicated by the polarity indicator 40, the stationary contact 71 is positive and the stationary contact 72 is negative at the crest of the wave, when the bridging conductors 143 and 144 are positioned, as shown in Fig. 1, to connect the 40 stationary contacts 71 and 72 with the stationary contacts 141 and 142 respectively. During the next quarter revolution of the rectifier disk 140 the current changes by one-half a complete cycle, and the stationary contacts 71 and 72 are negative and positive 45 respectively, when the bridging contacts 143 and 144 connect them with the stationary contacts 141 and 142 respectively. The rectifier, therefore, acts to take the higher voltage part of each wave of the high tension alternating secondary current of the transformer and to deliver the crest of all of the positive waves at the anode terminal through the contact 141 and conductor 150, 50 and to deliver the crests of all the negative waves at the cathode terminal through the contact 142 and conductor 151. As above explained, the polarity indicator 40 tells the operator which way to throw the 55 reversing switch 14 to have a positive polarity at the anode terminal A, and continues to indicate the polarity of the anode and cathode terminals. If the reversing switch should be thrown "Up" when the polarity indicator points "Down," the anode would

have a negative polarity, and the needle, by continuing to point "Down" while the reversing switch is "Up," would continue to notify the operator that the anode and cathode terminals had the wrong polarity. 70

The stationary contacts 71, 72, 141 and 142 are mounted upon the ends of four hard rubber posts 152 which project from four brackets 153 on the end of the motor frame. Three of the brackets 153 are of metal, but 75 the fourth bracket which, as indicated in Fig. 4, projects toward the panel 4, is of hard rubber to guard against leakage discharges between it and the high tension terminals. The lead wires which go from 80 the stationary rectifier terminals to the transformer and to the anode and cathode terminals are inclosed in hard rubber tubes 154. In order to rigidly space the stationary rectifier contacts apart and hold them 85 in a fixed relationship to the periphery of the disk, hard rubber braces or supports 155 extend between the adjacent hard rubber posts 152. The rectifier disk 140 is mounted on the motor shaft and the hard 90 rubber supporting frame for the stationary contacts is mounted on the motor casing, so that the stationary contacts and movable disk can be fixed in very exact spaced relation to each other. 95

The anode and cathode terminals A and C are similar in construction and project from the face of the hard rubber panel 4. The construction of these terminals is shown in more detail in Fig. 5, which is a section of 100 the anode terminal. A hard rubber bushing 160 fits through a hole in the hard rubber panel 4 and is clamped in place by two collars 161 and 162 threaded on the bushing 160 and bearing against the front and back of 105 the panel. In the end of the bushing 160 is a socket in which is received the end of a hard rubber sleeve 163. The sleeve 163 makes a frictional fit in the bushing socket and is held from rotation therein by means 110 of a spline 164. Extending through the bushing 160 is a conducting sleeve 165 having a flanged forward end to keep it from being pulled backward through the bushing. The sleeve 165 is firmly clamped in position by a nut 167 threaded on the sleeve. Clamped beneath the nut is a terminal piece 168 to which the high tension lead 150 is soldered. Rotatably mounted in the sleeve 165 is a conducting rod 170. The rod 170 120 carries, at its rear end, a hard rubber pulley 171. The forward end of the rod 170 is enlarged to form a socket 172 in which is frictionally held the split end of a second rod 173 which is loosely mounted to rotate 125 in the hard rubber sleeve 163. The end of the sleeve 163 is internally threaded to receive a thimble 174 into which the end of the conducting rod 173 loosely fits. The outer end of the thimble 174 has a hole through 130

which a flexible conducting cord 175 can be attached. A collar 176 is mounted to rotate on the thimble 174. Threaded in the radially extending hole in the collar is a spark gap arm 177, the reduced end 178 of which extends into a hole in the end of the rotatable rod 173. The upper part of the thimble 174 is cut away at 179 so that the arm 177 is free to turn rather more than half a circle. 5 The cut away portion 179 is formed by sawing partially through the thimble 174, leaving the bottom portion 180 of the thimble below the cut. The conducting cord 175 extends from the anode terminal to a hot wire 10 milliammeter 181 mounted on a bracket 182 upon the casing. On the side of the milliammeter is a spring-held spool 183 from which 15 can be drawn out a flexible metallic tape 184 for connection with the anode terminal 20 of the X-ray tube 10. The construction of the cathode terminal is substantially the same as that of the anode terminal, the only difference being that the spool 183 which carries the flexible tape 184 for the cathode 25 terminal of the X-ray tube is mounted upon the spark arm 185 of the cathode terminal. On the rear of the cathode terminal is a hard rubber pulley 186 similar to the pulley 171 of the anode terminal. The pulleys 171 30 and 186 are connected together and to the pulley 188 by means of string belts 187. The pulley 188 is turned, through beveled gears 189, by means of a hard rubber handle 190 at the front of the machine. When the 35 handle 190 is turned, the pulleys 171 and 186 turn the arms 177 and 185 toward or from each other to vary the spark gap between their ends, so that the sparking distance of 40 the current can be determined. On the lower part of the hard rubber panel is mounted a regulating arm R for use with X-ray tubes which have a chemical chamber for lowering the vacuum. The construction and mounting of the regulating arm R is 45 shown in detail in Fig. 6 and resembles that of the anode and cathode terminals. Like the anode terminal, the regulating arm R is mounted in a collar 200 which is rotatably mounted on a thimble 201 threaded on the 50 end of a hard rubber sleeve 202. The arm R is turned by means of rods 203 and 204 which extend through the sleeve 202 and bushing 205. A pulley 206 is mounted on the rear of the rod 204 and is connected, by 55 a string belt 207, to a pulley 208 which is turned, through beveled gears 209, by a hard rubber handle 210. By means of the handle 210, the arm R can be swung up toward the cathode terminal C to let a shunt current 60 flow through the chemical chamber 220 of the X-ray tube in order to lower its vacuum. In order that an excessive current may not pass through the chemical chamber 220, a high resistance 230 is inserted between the 65 chemical chamber 220 and the regulating arm R. This high resistance consists of a mixture 221 of graphite and plaster of Paris inclosed in a glass tube 222 which, in turn, is inclosed in a hard rubber tube 223 which is threaded on the end of the thimble 201. A 70 spring-pressed plunger 224 acts to hold the powdered material together. The spring-pressed plunger 224 is mounted in, and is electrically connected with, a terminal knob 225. The terminal knob 225 has a hole 75 through which is passed a flexible conductor 226 which leads to the chemical chamber 220 of the X-ray tube. In order to lower the vacuum of the tube, the operator turns the knob 225 and brings the regulating arm R 80 toward the cathode terminal C until the current jumps the gap between the end of the arm R and the cathode terminal. The passage of the current liberates the gas from the material, preferably asbestos wool, and 85 after the vacuum is sufficiently reduced, the operator swings the arm R out of sparking distance from the cathode terminal. 90 While the preferred embodiment of the present invention has been specifically illustrated and described, it is to be understood that the present invention is not limited to such embodiment, but may be embodied in other constructions within the scope of the invention as set forth in the following 95 claims:—

1. The combination of a self-contained X-ray apparatus comprising a step-up transformer, and terminals by which the transformer may be connected with an external 10 source of current; an electric instrument; and conductors for connecting the instrument with the secondary winding of the transformer to indicate an electrical condition therein; one of said conductors being 11 connected, by conductors embodied in said self-contained apparatus, with one of said terminals, so as to ground the instrument automatically upon the source of current whenever the latter is connected with the 1 said terminal.

2. Self-contained X-ray apparatus having, in combination, a step-up transformer; terminals by which the transformer may be connected with an external source of current; conductors by which an electric instrument may be connected across a few turns of the secondary winding of the transformer, at a point of substantially zero potential; and a permanent connection between 1 one of said conductors and the primary winding of the transformer, whereby an instrument connected as aforesaid may be grounded upon the source of current by way of the primary winding and the terminals.

3. A high potential rectifying commutator comprising a rotary member of insulating material having oppositely disposed arcuate conducting plates each extending along about 90° of the periphery of the 1

member, the periphery of said insulating member being cut away back of each arcuate conducting plate, means for driving the member, and four stationary contacts located about 90° apart around the member.

4. A high potential rectifier comprising a rotary member of insulating material having oppositely disposed bridging conductors at its periphery, a synchronous motor for driving the rotary member having a shaft on which the rotary member is mounted, stationary contacts mounted around the periphery of the member, and supporting means for the stationary contacts extending directly and rigidly from the motor casing.

5. A high potential rectifying commutator having, in combination, a rotary member of insulating material having oppositely disposed bridging conductors spanning about 90° of the periphery of the member, the periphery of said insulating member being cut away behind each bridging conductor, a motor for driving the member and four stationary contacts located about 90° apart around the member.

6. A high potential rectifier comprising a rotary disk of insulating material having

oppositely disposed bridging conductors spanning about 90° of the periphery of the disk, a motor for driving the disk having a shaft on the end of which the disk is mounted, four stationary contacts located about 90° apart around the disk, and means for rigidly supporting the stationary contacts including four posts of insulating material extending from the motor casing and rods of insulating material connecting adjacent posts for bracing them.

7. A high potential rectifier comprising a rotary disk of insulating material having oppositely disposed bridging conductors spanning about 90° of the periphery of the disk, a synchronous motor for driving the disk having a shaft on the end of which the disk is mounted, four stationary contacts located about 90° apart around the disk, and means for rigidly supporting the stationary contacts including four posts of insulating material extending from the motor casing.
